(57) CLAIM

The ornamental design for an American flag style cover for barbecue or the like, substantially as shown and described.

DESCRIPTION

In a preferred embodiment, the nature of this product is as an outdoor furniture cover, which is primarily useful for covering barbecues.

FIG. 1 is a front view of an American flag style cover for barbecue or the like, the opposite view being a mirror image;

FIG. 2 is a right side view thereof;

FIG. 3 is a left side view thereof;

FIG. 4 is a top plan view thereof; and,

FIG. 5 is a bottom plan view thereof.

The broken line showing a barbecue in the Figures is for illustrative purposes only and forms no part of the claimed design.
